ABSTRACT OF THE DISCLOSURE

The disclosure of the application is directed to a process for oxidizing certain soluble alkylene bisdithiocarbamates using hydrogen peroxide as the oxidizing agent without adding acid in an amount to convert all of the bisdithiocarbamate to the corresponding bisdithiocarbamic acid, under conditions to produce a soluble oxygen containing product. Such soluble oxygen containing product is thereafter treated with a solution of soluble salt of a divalent metal of zinc, manganese, copper or cadmium, thereby to precipitate a product containing oxygen and such divalent metal. The infrared absorption spectra of such products, and the method for combating fungus on growing agricultural crops, such as potato plants, are also described.

The present invention relates to novel derivatives of alkylene bisdithiocarbamic acids, and more particularly to oxidized alkylene bisdithiocarbamates derived from certain divalent metals, to the method of their preparation and to their uses, for example as biocides and agricultural fungicides.

The prior art discloses the zinc salts of ethylene bisdithiocarbamic acid (known in the trade as zineb), as well as the manganous salts of ethylene bisdithiocarbamic acid (known in the trade as maneb):

where X is the metal zinc or divalent manganese. Similar compounds of other metals are also known. These compounds can be prepared by treating the sodium salt of ethylene bisdithiocarbamic acid (nabam) in aqueous solution with a soluble zinc or manganous salt such as zinc or manganous sulfate and recovering the precipitated product that forms.

The prior art also discloses the manufacture of metal free oxidized products of soluble ethylene bisdithiocarbamates, the ethylene bisthiuram monosulfide and ethylene bisthiuram disulfide having the following formulas:

and

The latter compounds are prepared from ammonium or soluble metal ethylene bisdithiocarbamates by treating them with any of a variety of oxidizing agents and under a variety of conditions to produce the indicated compounds or mixtures of thiuram mono- and disulfides along with free sulfur and sometimes ethylenethiourea. Under acid conditions nabam oxidized with air in the presence of the manganous ion as catalyst, or the am-

2

monium salt oxidized with hydrogen peroxide at a pH of 6.5, yields ethylene bisthiuram disulfide. Under neutral conditions it yields polymeric ethylene bisthiuram monosulfide and under alkaline conditions, the monomeric ethylene bisthiuram monosulfide is obtained.

It has now been discovered that the oxidation of soluble ethylene bisdithiocarbamate under certain prescribed conditions, hereinafter more fully set forth, results in the formation of a new oxygen-containing material which forms divalent metal salts. Such materials have also been found to possess very desirable properties.

Hydrogen peroxide is the only oxidizing agent that has been found which will produce the compounds of the invention. The optimum quantity of hydrogen peroxide is two moles per mole of dithiocarbamate. The reaction is believed to take place in accordance with the following equation:

The oxidized nabam or equivalent soluble salt of another metal is then treated with a soluble salt of one of the divalent metals, zinc, manganese, cadmium or copper to precipitate the desired product which is removed by filtration.

The use of less than two moles of hydrogen peroxide results in a mixture of the metal salt of the unoxidized ethylene bisdithiocarbamate and the metal salt of oxidized alkylene bisdithiocarbamate. The use of more than two moles of peroxide results in the formation of some water-insoluble thiuram mono- and disulfides which do not form metal salts.

The important feature of the process of the invention in addition to the use of hydrogen peroxide as the oxidizing agent is avoiding the addition of acid during the oxidation step. If the stoichiometric amount of acid is present to convert all of the original soluble salt to the dithiocarbamic acid, the product will of course be substantially all the thiuram mono- and disulfides described above. However, by reducing substantially the amount of acid incorporated during the oxidation step, the oxygen becomes associated with the sulfur atoms of the dithiocarbamic acid, so that when the oxidized material is subsequently treated with a divalent metal, the desired compound containing both the divalent metal and the combined oxygen is obtained. Preferably no acid is added during the oxidation step. However, if an amount of acid between the stoichiometric amount and zero is added, the product will be a mixture of the thiuram mono- and disulfides and the desired product substantially in the proportions determined by the amount of acid added.

The temperature of the reaction should be maintained as low as practical, that is below about 40° C., preferably in the range of 0 to 10° C. This may be accomplished, for example, by ice-cooling to remove the heat generated by the exothermic reaction. The reaction is carried out with stirring over a time interval of about 30 minutes, followed by stirring an additional 0.5 to 2 hours at about 10 to 15° C. to complete the reaction. A light precipitate of free sulfur may form which can be removed by filtration.

A water-soluble salt of the desired divalent metal is then added to precipitate the insoluble salt of oxidized alkylene bisdithiocarbamic acid as a slurry. This precipitate is filtered, washed with water and dried in a low temperature oven.

In avoiding the formation of thiuram mono- and disulfides and providing the high yield of the oxygen-containing metal alkylene bisdithiocarbamates, it is impor-

tant to coordinate the time of reaction, the temperature and the degree of agitation. A short time of reaction at low temperature and greater intensity of agitation generally works toward the production of the highest yields of the desired product. If temperatures toward the higher end of the range are maintained, then the time permitted for the reaction should be shorter. However, if temperatures toward the lower end of the range are maintained, then a longer time of reaction is desirable.

As a starting material for the reaction any soluble metal salt of an alkylene bisdithiocarbamic acid may be used such as sodium, potassium or calcium. They correspond to the structural formula:

in which Z is a metal and x is twice the reciprocal of the valence of the metal (e.g., 2 in the case of sodium and 1 for calcium), and R is H or CH_3 .

The novel compounds of the invention are identified not only by the fact that they contain oxygen and one of the divalent metals as indicated above, but also by their infrared absorption spectra. The value of the infrared spectrum as a "fingerprint" identifying a chemical compound is well known and accepted. The technique is also useful in determining whether chemical manipulation of a compound with a known spectrum changes that compound in such a way as to eliminate some of its characteristic groupings of atoms and linkages and to introduce others with consequent changes in the infrared spectrum. Even if a new compound cannot be completely isolated or purified because of insolubility or because of inherent lability, its infrared spectrum will provide clues to its chemical identity.

Infrared spectra of the novel compositions of the invention, and those of related unoxidized alkylene bisdithiocarbamates and their oxidation products from the prior art were determined by the potassium bromide disc technique, unless otherwise indicated, in a Perkin-Elmer double beam spectrophotometer, and are presented in FIGURES 1 through 9.

FIGURE 1 is an infrared absorption spectrum of the zinc salt of oxidized ethylene bisdithiocarbamic acid as determined both by the potassium bromide disc technique, and by the Nujol mull technique (which resolves the 8.2μ absorption band);

FIGURE 2 shows the infrared spectrum of the zinc salt of partially oxidized nabam, that is the product formed when less than the stoichiometric two moles of hydrogen peroxide are used per mole of nabam;

FIGURE 3 shows the spectrum for zineb which is the zinc ethylene bisdithiocarbamate;

FIGURE 4 shows the infrared absorption spectrum for the manganous salt of oxidized nabam;

FIGURE 5 gives the infrared absorption spectrum for the manganous salt of partially oxidized nabam;

FIGURE 6 shows the infrared absorption spectrum for maneb which is the manganous ethylene bisdithiocarbamate;

FIGURE 7 shows the infrared absorption spectrum for ethylene bisthiuram disulfide which is an oxidation product of the ethylene bisdithiocarbamates and is known in the prior art;

FIGURE 8 also gives the infrared absorption spectrum for ethylene bisthiuram monosulfide, an ethylene bisdithiocarbamate oxidation product known in the prior art; and

FIGURE 9 gives the infrared absorption spectrum for the zinc salt of oxidized isopropylene bisdithiocarbamic acid.

In the drawings the abscissa represents the wavelength in linear fashion, expressed in microns, and the ordinate shows (to a logarithmic scale) the percent absorbance.

The novel compositions of the invention are shown by their infrared spectra to differ from both the correspond-

ing metal salts of unoxidized alkylene bisdithiocarbamic acid and from the prior art oxidation products thereof. Comparison of the infrared absorption bands in FIGURES 1, 4 and 9 with those of FIGURES 3, 6, 7 and 8 shows that a new band is present in the 5.8μ region of the oxidized products of the invention. This band is considered to be due to the presence of the carbonyl group, $C=O$, in the

group, resulting from sulfur-oxygen interchange. The same band appears in the infrared spectra of the copper and cadmium salts of oxidized ethylene bisdithiocarbamic acid. The products of the invention are also seen to lack many of the bands which appear to be characteristic of the thiuram monosulfide, as well as the $10.5-10.6\mu$ band present in the thiuram disulfide and in unoxidized ethylene bisdithiocarbamates.

Various preparations of the composition of the invention may differ considerably in elementary analysis, apparent empirical formula, but they nevertheless still give basically the same infrared absorption spectra indicating that the different preparations indeed contain basically the same new chemical substance or substances. We believe that the structure of the product formed by our process may have an open chain or polymeric form of structure which may contain recurring units as shown below:

where

$R=CH_3$ or H

$n=1$ or more (the structure being cyclic when n is 1), and

X is the divalent metal.

Our best analytical data indicate that the major portion of our product is a material described by the above empirical formula with possibly about 25% of the material having a formula which could be written as follows:

where R, n and X have the values assigned above.

We believe that the compound shown in Formula 2 would be a natural decomposition product of the compound of Formula 1.

Typical preparations of the novel compositions follow.

Example 1.—Zinc salt of oxidized ethylene bisdithiocarbamic acid

To a cooled solution of sodium ethylene bisdithiocarbamate (116.4 g. of 22% active material, or 0.1 mole) was added hydrogen peroxide (13.6 g. of 50% active or 0.2 mole) in 100 ml. water dropwise over a period of 30 minutes while maintaining the temperature of the reaction mixture below $40^\circ C$, preferably at $10-20^\circ C$. After standing for two hours, the mixture was filtered to remove a small quantity of pale yellow solid which precipitated during the peroxide addition. To the filtrate was added, with stirring, 100 ml. of 1 M zinc sulfate solution (0.1 mole). The pH of the aqueous solution of nabam before oxidation was 10.5; after oxidation it was 9.5-11.0; after the addition of the zinc sulfate solution the pH dropped to 5-7. The resulting yellow slurry was stirred for one hour, filtered, and the precipitate washed with water, then dried in an oven at $60^\circ C$. The solid melted at $180-230^\circ C$. with decomposition.

Analysis.—C, 16.41%; H, 2.20%; N, 9.12%; S, 35.94%; Zn 20.85%; O, 12.0%. Infrared absorption bands occur at 5.8, 6.3, 6.75, 7.6, 8.2, 9.1, 10.1 and 11.8μ as shown in FIGURE 1.

Example 2.—Zinc salt of oxidized 1,2-propylene bisdithiocarbamic acid

To sodium 1,2-propylene bisdithiocarbamate (the propylene group is the methyl ethylene group) (220 ml. of 24.5% active solution, 0.2 mole) in 200 ml. water was added dropwise with stirring and cooling hydrogen peroxide (27.2 g. of 50% active material, 0.4 mole) in 100 ml. water. The temperature of the reaction mixture was maintained at 5° C. over the 30-minute period of peroxide addition. The clear, orange-colored reaction solution was stirred for an additional 30 minutes at 10° C. At the end of this time, the solution was still clear. To this oxidized dithiocarbamate solution was then added 200 ml. of 1 M zinc sulfate solution (0.2 mole) with stirring. The resulting yellow slurry was stirred for one hour, filtered, washed, and dried at 50° C., yielding 58 grams of a solid melting at 180–200° C. The infrared absorption spectrum of the product is presented in FIGURE 9. It is similar to that of the zinc salt of oxidized ethylene bisdithiocarbamic acid prepared according to Example 1 except that with the propylene compound there are additional absorption bands at 6.9, 7.25, 7.6, 9.5, and 9.8 μ .

Example 3.—Cadmium salt of oxidized ethylene bisdithiocarbamic acid

To sodium ethylene bisdithiocarbamate (2328 g. of 22% solution, 2 moles) cooled by the addition of 4000 g. of chopped ice was added hydrogen peroxide (272 g. of 50% active, 4 moles) in 800 ml. water. The peroxide was added dropwise with stirring over a period of 60 minutes while maintaining the reaction temperature at 10–15° C. As soon as the addition was completed, cadmium nitrate (617 g. of Cd(NO₃)₂·4H₂O in 1000 ml. water, 2 moles) was added to the oxidized sodium salt. The resulting pale yellow slurry was stirred for one hour, filtered, washed with water, and dried in the oven at 50° C. A yield of 708 g. of yellow solid melting at 180–230° C. (with decomposition) was obtained. The infrared absorption spectrum determined on a Nujol mull of this product showed absorption bands at 5.8, 6.3, 6.6, 6.8 (Nujol), 7.3 (Nujol), 7.5, 8.2, 9.1, 10.1, 10.3, 10.9, and 11.6 μ .

Example 4.—Manganese salt of oxidized ethylene bisdithiocarbamic acid

The procedure of Example 1 was followed, using 56 g. (0.05 mole) of sodium ethylene bisdithiocarbamate in 400 ml. water, oxidizing it with 6.8 g. of 50% active hydrogen peroxide (0.1 mole) in 80 ml. water at 10° C. over a period of one hour. To this solution was added manganese sulfate (50 ml. of 1 M solution, 0.05 mole), to obtain 8.6 g. of a light brown product which melted (with decomposition) at 250° C. Yield, 58% of theoretical. The infrared spectrum of this material determined on a potassium bromide disc had absorption bands at 5.9, 6.3, 6.9, 7.25, 7.6, 8.6, 10.1 and 11.8 μ , as shown in FIGURE 4.

Example 5.—Copper salt of oxidized ethylene bisdithiocarbamic acid

The procedure of the preceding example was followed, using 7.98 g. (0.05 mole) of anhydrous copper sulfate dissolved in 50 ml. water in place of the manganese sulfate. A dark brown solid, 11.3 g. or 66% of theoretical

and melting at 160–190° C. was obtained. The infrared spectrum as determined on a Nujol mull of the product had absorption bands at 5.8, 6.3, 6.65, 6.8 (Nujol), 7.35 (Nujol), 8.1, 8.4, 9.6, 10.05, 10.6 and 11.7 μ .

It is to be noted that the infrared study of these five salts of oxidized alkylene bisdithiocarbamic acids showed no evidence of the presence of thiuram mono- or disulfides, which materials are known to be formed by oxidation of alkylene bisdithiocarbamates under different conditions.

Example 6.—Zinc salt of oxidized ethylene bisdithiocarbamic acid 25%, with zinc salt of unoxidized ethylene bisdithiocarbamic acid (zineb) 75%

The zinc salt of a mixture containing 25% of oxidized ethylene bisdithiocarbamic acid and 75% of unoxidized ethylene bisdithiocarbamic acid was prepared by the procedure of Example 1, using 2 moles of sodium ethylene bisdithiocarbamate (2329 g. of 22% active) and 68 g. (1 mole) of hydrogen peroxide 50% active in 200 ml. water, just sufficient to oxidize 25% of the dithiocarbamate present. To the resulting clear, orange-colored solution was added zinc sulfate (323 g. or 2 moles ZnSO₄·H₂O in 1 liter water) with stirring. The resulting slurry was stirred for one hour, filtered, and the filter cake washed with water and dried in a vacuum oven at 55° C. Yield, 537 g. of white solid, M.P. 200–220° C. (with decomposition). The infrared spectrum of the product, illustrated in FIGURE 2, shows absorption characteristics of the zinc salts of both the oxidized and the unoxidized ethylene bisdithiocarbamic acids.

Example 7.—Manganese salt of oxidized ethylene bisdithiocarbamic acid 25%, with manganese salt of unoxidized ethylene bisdithiocarbamic acid (maneb) 75%

The procedure of Example 6 was followed, substituting manganese sulfate (403 g. of technical 75% manganese sulfate, 2 moles, in 1 liter water) for the zinc sulfate. The resulting slurry was stirred for one hour, filtered, and the filter cake washed with water and dried as in the example above. Yield, 526 g. of tan colored solid, M.P. 115–135° C. (with decomposition). The infrared spectrum, illustrated in FIGURE 5, shows absorption characteristics of the manganese salts of both the oxidized and the unoxidized ethylene bisdithiocarbamic acids.

Example 8

Biological screening tests were conducted with the oxidized alkylene bisdithiocarbamates of the invention and the results are summarized below. Tests against the fungus *Aspergillus niger* were conducted by inoculating the test organism onto Mycophil agar plates prepared with serial dilutions of the test compounds. The inoculated plates were incubated for 96 hours at 77° F., and the lowest concentration of test compound which completely inhibited fungal growth was recorded in parts per million (p.p.m.). Zone of inhibition tests against three representative bacteria, *Bacillus subtilis*, *Staphylococcus aureus*, and *Salmonella typhosa*, were conducted by placing discs dipped in various concentrations of the test compounds on agar plates seeded with one of the test organisms, then incubating the plates for 24 hours at 100° F. The lowest concentration of the test chemical producing a clear zone denoting absence of bacterial growth around the discs was recorded in p.p.m.

TABLE I.—MICROBIOLOGICAL SCREENING TESTS

Alkylene bisdithiocarbamate	Color	Lowest concentration inhibiting growth, p.p.m.			
		A. niger	B. subtilis	S. aureus	S. typhosa
Zinc oxidized-ethylene	Yellow.....	100	50	50	20-50
Manganese oxidized-ethylene	Tan.....	100	100	300	100
Cadmium oxidized-ethylene	Yellow.....	+1,000	50	300	300
Cupric oxidized-ethylene	Brown.....	+1,000	300	300	300
Zinc oxidized-propylene	Yellow.....	100	50	50	50

Key: + means "more than."

Example 9

Field trials of the compounds of the invention were carried out on growing potatoes in Florida. The fungicides were prepared in the form of wettable powders in the following formulation:

	Parts by weight
Experimental fungicide	65
McNamee clay ¹	27
Silene EF ²	5
Darvan No. 1 ³	2
Ultrawet K ⁴	1
	100

¹ Soft kaolin clay of R. T. Vanderbilt Company, Inc.

² Fine hydrated precipitated calcium silicate of Harwick Standard Chemical Co.

³ Polymerized sodium alkylnaphthalene sulfonate dispersant of R. T. Vanderbilt Company, Inc.

⁴ Alkyl benzene sodium sulfonate dispersant of Atlantic Refining Co.

The experimental fungicides were mixed with water at the rate of 2 pounds per 100 gallons, and were applied at the rate of 125 gallons or 225 gallons per acre of growing potatoes. All plots were sprayed at the same rate on a given date. Spraying was done on March 5, 12, 18, 22 and 28 and April 3, 10, 16, 23 and 30. Percent defoliation of the plants by blight was determined on April 12, 22 and 29 and on May 7 and 10. The yield of potatoes at harvest on May 13 was determined and is reported in the table below in pounds. One experimental plot was left untreated as a control.

TABLE II.—POTATO FIELD TRIALS

Ethylene bisdithiocarbamate	Average percent defoliation					Yield, lb.
	4/12	4/22	4/29	5/7	5/10	
None (untreated control)	10	25	40	177.5	287.5	² 156
Zinc, oxidized	2	7.5	22.5	57.5	80	177
Manganese, oxidized	3	3	22.5	55	75	209
Cupric, oxidized	10	15	35	55	72.5	171
Cadmium, oxidized	10	15	27.5	47.5	67.5	² 162

¹ Highly significant, two standard deviations.

² Significant, one standard deviation.

Considerable weight is usually given to the May 7 reading of defoliation. The May 10 reading determines the persistence of the fungicide. Thus, each of the compounds of the invention has been shown to be an effective agricultural fungicide specifically for combatting fungus on potato plants.

Example 10

Potato field trials were carried out on the efficacy of the completely and the partially oxidized zinc and manganese compounds in controlling early blight of potatoes. The field trials were carried out in the manner described and using formulations similar to those described in Example 9.

TABLE III.—POTATO FIELD TRIALS

Ethylene bisdithiocarbamate	Average percent defoliation					Yield, lb.
	4/12	4/22	4/29	5/7	5/10	
None (untreated control)	10	25	40	77.5	87.5	156
Zinc, 100% oxidized	2	7.5	22.5	57.5	80	177
Zinc, 25% oxidized (Example 6)	2	3	20	47.5	80	178
Manganese, 100% oxidized	3	3	22.5	55	75	209
Manganese, 25% oxidized (Example 7)	5	5	15	30	47.5	196

These data show that the oxidized and the partly-oxidized ethylene bisdithiocarbamates are effective against early blight of potatoes.

Example 11.—Zinc salt of oxidized ethylene bisdithiocarbamic acid, with thiuram sulfides

To the sodium salt of ethylene bisdithiocarbamic acid (116.4 g. of 22% active material, 0.1 mole) in 100 ml. water was added at 25° C., with cooling, hydrogen peroxide (6.8 g. of 50% active, 0.1 mole), sufficient to oxidize half the dithiocarbamate present to thiuram sul-

fides, and sulfuric acid (4.9 g. concentrated acid, 0.05 mole). The addition was made over a 30-minute period, and a white precipitate formed. After stirring for 15 minutes longer, the reaction mixture was cooled to 5° C. and a further quantity of hydrogen peroxide (6.8 g.) in 20 ml.

water was added over a 15-minute period to oxidize the remaining dithiocarbamate to the oxygen-containing product of the invention. The yellow slurry which formed was stirred for 15 minutes longer at 10–15° C., then zinc sulfate solution (50 ml. of 1 M solution, 0.05 mole) was added rapidly. The slurry changed to a pale yellow color. The final pH of the mixture was 6.5. The reaction mixture was stirred for an additional 30 minutes at room temperature and then filtered. After washing three times

with water and drying at 50° C. in a forced draft oven, a yield of 22 grams was obtained, M.P. 130–190° C. The infrared spectrum of a Nujol mull of the product showed bands at 5.8, 6.3, 6.6 (Nujol), 7.25 (Nujol), 7.5, 7.85, 8.2, 9.0, 9.45, 10.05, 10.45 and 11.75 μ , indicating the presence of the zinc salt of oxidized ethylene bisdithiocarbamic acid, thiuram sulfides, and a trace of the zinc salt of unoxidized ethylene bisdithiocarbamic acid (zineb).

Biological screening of this mixed product shows the following minimum concentrations, in parts per million, to be effective against these test organisms: *Aspergillus niger* 300, *Bacillus subtilis* 100, *Staphylococcus aureus* 100, and *Salmonella typhosa* trace at 20. In a soap plug test, carried out in accordance with the procedure described in U.S. Patent No. 2,977,316, diameters of the

zones of inhibition around plugs of soap in which the material was incorporated at 1% concentration were 20, 17, and 20 mm. respectively, for the test bacteria *B. subtilis*, *S. aureus* and *S. typhosa*.

Example 12.—Manganese salt of oxidized ethylene bisdithiocarbamic acid, with thiuram sulfides

The procedure described in Example 11 was repeated except that a soluble manganese salt was used instead of the soluble zinc salt, thereby forming a mixture of thiuram sulfides and the manganese salt of oxidized ethylene bisdithiocarbamic acid. The final slurry of solids was separated and purified and found to be a mixture of ethylene

thiuram monosulfide, ethylene thiuram disulfide, the manganese salt of oxidized ethylene bisdithiocarbamic acid and a small amount of maneb.

By using an amount of peroxide in excess of the amount needed for complete conversion to the oxidized alkylene bisdithiocarbamate, and/or by adding some acid during the oxidation step, the relative proportions of metal salt of oxidized nabam and ethylene bisthiuram sulfides may be varied. Such mixtures may contain from 20–80% ethylene bisthiuram sulfides and 80–20% metal salt of oxidized alkylene bisdithiocarbamate. Because of the active

properties as fungicides of the ethylene bis thiuram sulfides, such mixtures also have useful properties.

We claim:

1. The process which comprises oxidizing a soluble alkylene bisdithiocarbamate of the structure

where Z is a metal, x is twice the reciprocal of the valence of the metal, and R is a member of the group consisting of hydrogen and CH_3- , in solution with hydrogen peroxide without adding acid in amount to convert all of the bisdithiocarbamate to the corresponding bisdithiocarbamic acid, under conditions to produce a soluble oxygen-containing product, and controlling the amount of hydrogen peroxide used and limiting the amount of any acid added, to form said soluble product containing at least 5% oxygen, and thereafter adding to the solution a soluble salt of a divalent metal of the group consisting of zinc, manganese, copper and cadmium, thereby to precipitate a product containing oxygen and said divalent metal.

2. The process which comprises oxidizing a soluble alkylene bisdithiocarbamate of the structure

where Z is a metal, x is twice the reciprocal of the valence of the metal, and R is a member of the group consisting of hydrogen and CH_3- , in solution with hydrogen peroxide without adding acid in amount to convert all of the bisdithiocarbamate to the corresponding bisdithiocarbamic acid, under conditions to produce a soluble oxygen-containing product, and controlling the amount of hydrogen peroxide used and limiting the amount of any acid added, to form said soluble product containing at least 5% oxygen.

3. The process of claim 1 in which the dithiocarbamate has the structure shown in which R is hydrogen.

4. The process of claim 1 in which no acid is added during the process thereby to avoid the formation of substantial amounts of thiuram sulfides.

5. The process of claim 1 in which the amount of hydrogen peroxide used is about 2 moles per mole of alkylene bisdithiocarbamate.

6. The process of claim 1 in which the reactions are carried out in an aqueous solvent medium.

7. The process of claim 1 in which the temperature of the reaction medium during the oxidation reaction is maintained below about 40°C .

8. The process of claim 6 in which the temperature of the reaction medium during the oxidation reaction is maintained in the approximate range of $0-10^\circ \text{C}$. with agitation.

9. The process of claim 1 in which the dithiocarbamate has the structure shown in which R is hydrogen, and the divalent metal is zinc.

10. The process of claim 1 in which the dithiocarbamate has the structure shown in which R is CH_3- , and the divalent metal is zinc.

5 11. The process of claim 1 in which the dithiocarbamate has the structure shown in which R is hydrogen, and the divalent metal is manganese.

12. The process of claim 1 in which the dithiocarbamate has the structure shown in which R is hydrogen, and the divalent metal is copper.

13. The process of claim 1 in which the dithiocarbamate has the structure shown in which R is hydrogen, and the divalent metal is cadmium.

15 14. An oxygen-containing salt of an ethylene bisdithiocarbamic acid and a divalent metal selected from the group consisting of zinc, manganese, copper and cadmium, containing at least 5% of oxygen, and having substantially the infrared absorption spectrum shown in FIGURE 1, with absorption bands at 5.8, 6.3, 6.75, 7.6, 8.2, 10.1 and 11.8μ .

20 15. The compound described in claim 14 in which the divalent metal is zinc and having an infrared absorption spectrum characterized by bands at 5.8, 6.3, 6.75, 7.6, 8.2, 9.1, 10.1 and 11.8μ .

25 16. The compound described in claim 14 in which the divalent metal is manganese and having an infrared absorption spectrum characterized by bands at 5.9, 6.3, 6.9, 7.25, 7.6, 8.6, 10.1 and 11.8μ .

30 17. An oxygen-containing salt of propylene bisdithiocarbamic acid and a divalent metal selected from the group consisting of zinc, manganese, copper and cadmium, containing at least 5% oxygen, and having substantially the infrared absorption spectrum illustrated in FIGURE 9, with absorption bands at 5.8, 6.3, 6.7, 6.9, 7.25, 7.6, 8.4, 9.1, 9.5, 9.8, 10.2 and 11.8μ .

35 18. The compound described in claim 17 in which the divalent metal is zinc.

40 19. The compound described in claim 14 in which the divalent metal is copper and having an infrared absorption spectrum characterized by bands at 5.8, 6.3, 6.65, 8.1, 8.4, 9.6, 10.05, 10.6 and 11.7μ .

45 20. The compound described in claim 14 in which the divalent metal is cadmium and having an infrared absorption spectrum characterized by bands at 5.8, 6.3, 6.6, 7.5, 8.2, 9.1, 10.1, 10.3, 10.9 and 11.6μ .
